DESIGN FOR A COMBINED STAND AND HOLDER FOR CIGARETTES OR OTHER ARTICLES

George R. Thurman, St. Louis, Mo.

Application June 20, 1935, Serial No. 57,344

Term of patent 14 years

To all whom it may concern:

Be it known that I, George R. Thurman, a citizen of the United States of America, residing in the city of St. Louis and State of Missouri, have invented a new, original, and ornamental Design for a combined Stand and Holder for Cigarettes or Other Articles, of which the following is a specification, reference being had to the accompanying drawing, forming a part thereof.

The drawing is a perspective view of a combined stand and holder for cigarettes or other articles, showing my new design.

I claim:

The ornamental design for a combined stand and holder for cigarettes or other articles, substantially as shown.

GEORGE R. THURMAN.
